C. W. MACKENZIE

UNITED STATES PATENT OFFICE.

CYRUS W. MACKENZIE, OF WAWERLY, INDIANA.

BUCKET FOR FILLING AUTOMOBILE-RADIATORS.

1,167,380.

Specification of Letters Patent. Patented Jan. 11, 1913.

Application filed April 18, 1905. Serial No. 23,422.

To all whom it may concern:

Be it known that I, Cyrus W. Mackenzie, a citizen of the United States, residing at Waverly, in the county of Morgan and State 5 of Indiana, have invented certain new and useful Improvements in Buckets for Filling Automobile-Radiators, of which the following is a specification, reference being had to the accompanying drawings.

10 The present invention relates broadly to new and useful improvements in buckets and has especial reference to the provision of a novel form of water bucket adapted for use in filling automobile radiators.

15 The primary object of the invention is to construct a bucket of this character in which the bottom is provided with a normally closed valve, a funnel which may be inserted in the radiator cap, and a controlling arm 20 which is adapted to engage with the radiator cap and to open the valve to permit the flow of water from the bucket into the radiator when the funnel is inserted therein.

Another object is to provide a bucket of 25 this character which is relatively simple in construction and may, therefore, be cheaply manufactured.

The above, and other incidental objects of a similar nature, which will be hereinafter 30 more specifically treated are accomplished by such means as are illustrated in the accompanying drawings, described in the following specification, and then more particularly pointed out in the claim which is appended hereto and forms part of this application.

With reference to the drawings, wherein there has been illustrated the preferred embodiment of this invention, as it is reduced, 40 to practice, and throughout the several views of which similar reference numerals designate corresponding parts, Figure 1 is a side elevation of the bucket, showing the same applied to the filling cap of an automobile 45 radiator and illustrating the manner in which the valve controlling rod operates to open the valve; Fig. 2 is a section on the line 2—2, of Fig. 1; Fig. 3 is a section on the line 3—3, of Fig. 1; Fig. 4 is a section on the line 4—4, of Fig. 1; Fig. 5 is a detail top plan view of the valve and seating frame thereof; and Fig. 6 is a detail view of the valve controlling rod.

As best disclosed as an entirety in Fig. 1 55 of the accompanying drawings, the bucket consists broadly in a bottom 10, a flexible

side wall 11, a funnel tube 12, a valve 13 and a valve controlling rod or arm 14. The bottom wall 10 is preferably formed from a circular sheet of metal, although wood or any similar equivalent material may be employed, if desired. The side wall 11 is preferably formed of water proof canvas or some equivalent fabric. Any water-proof material of a flexible nature, other than canvas, may be employed, without departing in any way from the spirit of the invention. The lower edge of the side wall is secured by a binding hoop or ring 15, the internal rim 16 of which seats in a facial groove 70 formed in the flange 16' of the bottom wall and serves to tightly clamp the fabric therein. If the bottom wall is formed of wood, the side wall may be secured by tacks or equivalent elements. 75

The upper end of the side wall is preferably provided with a stiffening ring 17, to which a handle 18 may be attached, if desired. In the approximate center of the bottom wall is formed an opening or port 19 through which the water is adapted to be passed into the funnel 12. The funnel preferably consists of a tube, the upper end of which is provided with an annular out-standing flange 20, through which screws, 66 rivets or equivalent fastening devices may be passed in securing the funnel to the bottom wall. The valve 13 preferably consists in a small flap of leather or equivalent material which is secured at one terminal, as by a screw or rivet 21 to the inner face of the bottom wall, so that its free end is positioned over the opening 19 and is provided upon its upper face with a wear plate 22. The free end of a leaf spring 23 bears upon 85 this wear plate and normally holds the valve in closed position.

The valve controlling rod heretofore designated by the numeral 14 is preferably formed from a single length of wire which is bent at its one terminal to produce a longitudinal arm 24 and at its other terminal to form a goose-neck hook 26. The arm 24 is secured firmly against the bottom wall to the lower face thereof and is bent downwardly 105 at its junction with the body portion 25 of the controlling rod, as indicated at 27 so that the member 26 is normally held in spaced relation to the bottom wall. The bill of the goose-neck is of such length that 110 it passes upwardly through the funnel and is maintained in intimate contact or engage-

ment with the lower face of the valve by the inherent resiliency of the arm or rod 24. It is also to be noted that the tension of the spring 23 is greater than the tension of the arm 24 so that the valve 13 is normally maintained in closed adjustment.

- Upon reference now to Fig. 1 it will be readily discerned that when the bucket is filled with water and the funnel is inserted 10 in a radiator cap, the weight of the bucket will be sufficient to move the bottom wall thereof downwardly against the tension of the valve spring, so that the bill of the goose-neck hook will force the valve into open position against the tension of the valve spring. In this connection it is to be noted that the body portion 26 of the controlling rod rests upon the edge of the radiator cap and that the hook member is inserted therein with 15 the funnel. It will also be observed that the valve spring is not of sufficient strength to support the weight of the bucket and, as a result, this member rests upon the body portion 26 of the controlling rod, thereby 20 maintaining the valve in open position and allowing the water to flow from the bucket into the funnel and into the radiator.
- In reduction to practice, it has been found 25 that the form of this invention illustrated in the drawings and referred to in the above description as the preferred embodiment is the most efficient and practical; yet realizing that the conditions concurrent with the adoption of this device will necessarily vary, it is desirable to emphasize the fact that 30 various minor changes in the details of construction, proportion and arrangement of

parts may be resorted to, when required, without sacrificing any of the advantages of this invention, as defined by the appended 40 claim.

What is claimed is:—

A container including a body having an opening in its bottom wall, said opening being defined by a depending tube, a flap valve 45 secured within the body and to the bottom wall thereof at one side of the opening, said valve overlying the opening in the bottom wall, a spring positioned within the body secured to the bottom wall thereof at one side 50 of the opening and at a point substantially diametric to the point of connection between the valve and bottom wall, said spring overlying the valve for normally maintaining the same in a closed position, and a resilient 55 rod having one extremity secured to the outer face of the bottom wall of the body and terminating in a goose-neck extension bridging the wall of the depending tube, the free extremity of said extension passing inwardly of the tube and in constant contact 60 with the flap valve whereby inward movement of the rod relative to the body forces said flap valve into open position, the tension of the rod being less than the tension 65 of the spring, whereby the valve is maintained normally closed.

In testimony whereof I hereunto affix my signature in the presence of two witnesses.

CYRUS W. MACKENZIE.
